Primary Examiner — Jae Liang*Assistant Examiner* — Jane Yoon(74) Attorney, Agent, or Firm — Kunzler Bean & Adamson, PC; Michael Bartholomew(57) CLAIM

The ornamental design for a VR storage bag as shown and described.

DESCRIPTION

FIG. 1 is a front, right and top perspective view of a VR storage bag, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front, right, and top perspective view the VR storage bag of FIG. 1 shown in an opened configuration. The broken lines depict the zipping portions of the VR storage bag and form no part of the claimed design.

1 Claim, 9 Drawing Sheets
